UNITED STATES PATENT OFFICE

119,589

DESIGN FOR A GAME BOARD

Lyndell F. Johnson and Leo H. Wilson,
Edwardsville, Ill.

Application July 10, 1939, Serial No. 85,928

Term of patent 7 years

To all whom it may concern:

Be it known that we, Lyndell F. Johnson and Leo H. Wilson, citizens of the United States of America, and residing at Edwardsville, in the county of Madison and State of Illinois, have invented a new, original, and ornamental Design for Game Boards, of which the following is a specification, reference being had to the accompanying drawing, forming a part thereof, wherein

We claim:

The ornamental design for a game board, substantially as shown.

LYNDELL F. JOHNSON.
LEO H. WILSON.
